US00D741387S

(12) **United States Design Patent**
Parrot

(10) **Patent No.:** **US D741,387 S**
(45) **Date of Patent:** **** Oct. 20, 2015**

(54) **ARTICULATED TOOL-HOLDING ARM**

(71) Applicant: **TECNOSPIRO MACHINE TOOL, S.L.**, Barcelona (ES)

(72) Inventor: **Ramon Jou Parrot**, Barcelona (ES)

(73) Assignee: **TECNOSPIRO MACHINE TOOL, S.L.**, Barcelona (ES)

(**) Term: **14 Years**

(21) Appl. No.: **29/477,063**

(22) Filed: **Dec. 19, 2013**

(30) **Foreign Application Priority Data**

Jun. 19, 2013 (EM) 002258442-0013

(51) LOC (10) Cl. **15-99**

(52) U.S. Cl.

USPC **D15/199**; D15/140

(58) **Field of Classification Search**

USPC D15/140, 199

See application file for complete search history.
